UNITED STATES PATENT OFFICE.

PETER D. THROPP, OF TRENTON, NEW JERSEY, ASSIGNOR TO THERMOID RUBBER CO.,
OF TRENTON, NEW JERSEY, A CORPORATION OF NEW JERSEY.

DESIGN FOR A TIRE TREAD.

Application filed May 17, 1922. Serial No. 2,297. Term of patent 14 years.

To all whom it may concern:

Be it known that I, PETER D. THROPP, a citizen of the United States, and resident of Trenton, in the county of Mercer and State of New Jersey, have invented a new, original, and ornamental Design for a Tire Tread, of which the following is a specification, reference being had to the accompanying drawing, forming part thereof.

My new design for a tire tread is shown in the accompanying drawing, in which—

Fig. 1 represents a plan view of a portion of a tire casing.

Fig. 2 represents a transverse section taken in the plane of the line II—II of Fig. 1.

What I claim is:

The ornamental design for a tire tread substantially as shown.

PETER D. THROPP.
